3 Claims

ABSTRACT OF THE DISCLOSURE

Monoalkali metal and monoammonium salts of di-corticoid phosphates have the peculiar property that under certain circumstances they are able to react with free corticoids to form water-soluble compounds therewith whereby the solubility increases 300 to 600 times that of nonreacted corticoids and, in all cases tried, reaches a value of more than 0.2 mg. per ml., which allows the admission of therapeutic doses by way of injection of one or a few milliliters of water; and the bond secured is of loose character clearly demonstrated by removal of the free corticoid quantitatively upon shaking with water.

The invention concerns water-soluble corticoid compounds that decompose instantaneously in plasma or tissue fluid with liberation of corticoid in free form. Furthermore the invention concerns a method of producing said compounds. The compounds in question are especially effective for treating shock and shock-like conditions.

It is known to apply corticoids effective against said conditions, such as hydrocortisone and cognate substances in the form of an alcoholic suspension of a free corticoid mixed with aqueous infusion liquids, to be administered intravenously by infusion when a quick effect had to be obtained. However, the administration of medicines in the form of infusions has the drawback that special equipment is necessary for carrying out the infusion, which ordinarily necessitates that the patient be hospitalized. Furthermore, carrying out the preparatory measurements for the infusion is time consuming and the infusion process itself takes a long time, in most cases at least a couple of hours.

In order to avoid such drawbacks water-soluble corticoid compounds have been produced, ordinarily in the form of esters, the solubility of which is sufficient to make it possible to introduce in the patient the necessary amount of corticoid by injecting a small volume, for instance 1 ml. of a liquid in which it is contained. In many cases such injections may be given intravenously. Consequently the medicament can be brought into the blood stream and distributed therein in the course of a few minutes after the patient has been brought under the care of a doctor. However, this mode of administration has the drawback that the compounds in question are true chemical derivatives which must be decomposed in the organism to split off the free corticoid before the effect takes place. The process is an enzymatic one caused by substances, for instance esterases, present in the blood stream. Consequently a considerable time passes until the injected amount of corticoid has been converted into a form in which it is available to the organism.

It would be desirable to have water-soluble corticoids which would split off instantaneously the effective corticoid on injection into the blood circulation, so that the effect would be instantaneous.

It has now been found that monoalkali metal and monoammonium salts of di-corticoidphosphates have the

2

peculiar property that under certain circumstances they are able to react with free corticoids to form water-soluble compounds therewith. Hereby the solubility increases to 300–600 times the solubility of non-reacted corticoids and in all cases tried, reached a value of more than 0.2 mg. per ml., which is sufficient to allow the administration of therapeutic doses by way of injection of one or a few milliliters of water. The bond, by which this increased solubility has been secured is, however, of a somewhat loose character which is clearly demonstrated, i.e., by the fact that the free corticoid may be removed quantitatively from the compound by shaking an aqueous solution of the compound with water.

The character of the binding is not known, and it is unsure whether it takes place in fixed stoichiometrical proportions or not.

According to the invention such water-soluble corticoid compounds which in plasma or tissue fluid are split up instantaneously while giving off free corticoid are produced by contacting an aqueous solution of mono-alkali-metal salt of di-corticoidphosphate or a corresponding ammonium salt with a solution of corticoid in a solvent which is at least partly miscible with water.

Hereby the desired product is obtained which when injected is found to have an instantaneous effect corresponding to the amount of free corticoid used for the preparation. The amount of corticoid used as phosphate is liberated gradually in the organism. Consequently the preparation is very well suited for use in the treatment of shock or shock-like conditions.

According to a preferred embodiment of the invention the reaction mixture is transformed into a homogeneous solid state in which it is stable which is shown by the fact that it dissolves to form clear solutions at the above-mentioned high and in some cases even higher concentrations, which solutions when used for injections show the abovementioned effect.

According to a further preferred embodiment of the invention the transformation of the reaction mixture into a homogeneous solid state takes place by freeze-drying, so-called, i.e., a drying process at such low temperature that the reaction mixture stays solid. It has been found that the mixture stands the freezing very well and that the product obtained when adding thereto the amount of water necessary to form a concentrated solution dissolves spontaneously to form a clear liquid which may be injected intravenously.

It has further been found that the 21-phosphates of corticoids may be used for the di-steroid-phosphate, and in connection therewith the same or another corticoid in free form may be used, subject to the condition that it has a hydroxyl group in the 11- or the 21-position. Exactly these corticoids are generally well suited for the treatment of shock or shock-like conditions.

Experiments have been carried out with salts of dihydrocortisone-21-phosphate and of di-prednisolone-21-phosphate, but also the mono-salts of other di-corticoid-phosphates are assumed to be effective. By way of example corticosterone, hydrocortisone, prednisolone and dexamethazone are mentioned as substances which when used for the free steroid component have shown the effect described above, but substitution derivatives are supposed to work in the same manner. In contrast thereto the effect does not take place when other steroids such as oestradiol, progesterone or testosterone are used. The effect does not either take place if the corticoid or the corticoidphosphate is simply dried.

As solvent for the steroid component any solvent or mixture of solvents which is suitable for dissolving the corticosteroid in question can be used, provided that it is partly or completely miscible with water. By way of examples of such solvents may be mentioned ethanol, meth-

anol, dioxane, pyridine, mixtures of pyridine and benzene, dimethylformamide and many others. Care must be taken that during the conversion of the reaction mixture into solid state no separation of solid steroid takes place. Such separation can in any case be easily avoided when said conversion takes place by way of freeze-drying.

The amount of the steroid in proportion to the amount of the phosphate may be varied within wide limits, in any case within the limits 1 to 3 mol steroid per mol steroidphosphate. However, a mol ratio of about 1:1 seems to be especially well suited. With increasing contents of free corticoid difficulties with the freeze-drying process may be encountered, since increased contents of corticoid in the mixture necessitates higher concentrations of organic solvents, whereby the freezing temperature is decreased.

EXAMPLE

1% solutions of the corticoids mentioned below in organic solvents are mixed with 1% solutions of di-hydrocortisonephosphate-monosodium salt in water in the ratios stated, which correspond to the mol ratio 1:1, whereupon the mixtures are freeze-dried.

Steroid	Solvent for the steroid	Percent steroid	Percent ester	Steroid solubility in water (mg./ml.)	Solubility in water of the mixed compound (mg./ml.)
Cortico-sterone.....	Ethanol.....	30.0	70.0	0.2	200
Hydrocortisone.....	Methanol.....	31.0	69.0	0.2	200
Prednisolone.....	Dioxane.....	30.8	69.2	0.2	200
Dexamethazone.....	Pyridine.....	32.7	67.3	0.2	200

Corresponding compounds may be produced by substituting di-prednisolone phosphate monosodium salt for the di-hydrocortisone phosphate monosodium salt. The solubility of the addition compound hereby surpasses 50 mg./ml. in all cases tried.

By injection in rats weighing 250 g. of the addition compound mentioned in the above example, consisting of 31% hydrocortisone and 69% di-hydrocortisone phosphate monosodium salt, in an amount of 0.5 mg. dissolved in 1 ml. of water the following concentrations of hydrocortisone in the plasma were found in γ /ml.:

Time after injection: γ /100—30 sec., 136; 5 min., 80; 30 min., 2.5; 60 min., 0.

Whereas injection of 0.35 mg. di-hydrocortisone phosphate monosodium salt dissolved in 1 ml. of water did not produce ascertainable hydrocortisone contents in the plasma during the experiment period. This shows that the loosely bound hydrocortisone is liberated immediately upon the injection whereas the ester-bound hydrocortisone is so slowly liberated that the analytic method used is not

sensitive enough for registering it after 60 minutes. The analytic method used is: J. van der Vies, *Acta Endocrinologica* 38, 399 (1961).

Pigs weighing 25-30 kgs. were brought into ether-nembutal narcosis until shock-condition started. The abdomen was opened and it could be seen that the peristaltic movement had ceased and that the colour of the intestines was cyanotic. By intravenously injecting 100 mg. of the same addition compound as mentioned above in 1 ml. of water, the peristaltic movement started again 30-60 seconds after the injection and the intestines again assumed their normal colour.

What is claimed is:

1. Process of producing water-soluble corticoid compositions which decompose instantaneously into plasma or tissue fluid with liberation of corticoid in free form, which comprises reacting an aqueous solution of a substance of the class consisting of the monoalkali metal salt of dicorticoid phosphate and the ammonium salt of dicorticoid phosphate with a solution of corticoid in a solvent which is at least partly miscible with water, hydrocortisone and prednisolone as dicorticoid phosphate, and hydrocortisone,

prednisolone and dexamethazone as free steroids, being employed, and transferring the reaction mixture into homogeneous solid state.

2. Process according to claim 1 wherein the reaction mixture is subjected to freeze-drying.

3. Process according to claim 2 wherein the phosphate is a 21-phosphate and the corticoid used in its free form has a hydroxyl group either at the 11- or 21-position.
